(57) **CLAIM**

The ornamental design for a vehicle headlight, as shown and described.

DESCRIPTION

FIG. 1 is a left side elevational view of a left vehicle headlight (the right vehicle headlight being a mirror image and is not shown);

FIG. 2 is a right side elevational view of the vehicle headlight; FIG. 3 is a front elevational view of the vehicle headlight; FIG. 4 is a top plan view of the vehicle headlight; FIG. 5 is a bottom plan view of the vehicle headlight; FIG. 6 is a perspective view of the vehicle headlight; and, FIG. 7 is another perspective view of the vehicle headlight. The vehicle headlight is intended to be observed in various states of internal illumination as well as in daylight with no internal illumination.
